LE ROY WERTS, OF MILFORD, MISSOURI.

PRIMING ATTACHMENT FOR INTERNAL-COMBUSTION ENGINES.

1,221,782.

Specification of Letters Patent.

Patented Apr. 3, 1917.

Application filed July 17, 1916. Serial No. 109,814.

To all whom it may concern:

Be it known that I, LE ROY WERTS, a citizen of the United States, residing at Milford, in the county of Barton and State of Missouri, have invented certain new and useful Improvements in Priming Attachments for Internal-Combustion Engines, of which the following is a specification.

This invention relates to priming attachment for automobile engines and has for its object to produce an attachment of this character which will be found especially serviceable in starting the engines of motor cars and the like, particularly in cold weather, a further object being to produce a simple, strong, durable, cheap and efficient attachment for the purpose named, which can be easily and economically applied to a motor car.

With these general objects in view, the invention consists in certain novel and peculiar features of construction and organization of parts as hereinafter described and claimed; and in order that it may be fully understood, reference is to be had to the accompanying drawing, in which—

Figure 1, is a fragmentary plan view of a motor car equipped with an attachment embodying my invention.

Fig. 2, is an enlarged section taken on the line II—II of Fig. 1, the gasolene priming tank being shown in elevation.

Fig. 3, is an enlarged section of the nozzle of the priming attachment.

Fig. 4, is a side elevation of a modified construction of the attachment.

In the said drawing, 1 indicates the dash, 2 the engine, 3 the carbureter and 4 the manifold connecting the carbureter with the engine in the customary or any preferred manner. 5 is a tank or cup containing gasolene for priming purposes. Said tank is provided with a discharge pipe 6 controlled by a valve 7, and communicating with a mixing tube 8, the discharge pipe at its point of communication with the tube 8 being reduced in diameter to approximately one sixty-fourth of an inch, so that only an exceedingly fine or small drop or stream of the gasolene can pass through it into the mixing tube 8, and thus enable the blast of air hereinafter mentioned to instantly convert such gasolene into vapor. The mixing tube 8 projects into the manifold 4 and is secured thereto with an air tight relation, and terminates in a nozzle 9 having small radiating

jet orifices 10 for discharging a combustible mixture into the manifold, which as the engine is cranked, will be sucked into the cylinders in proper order for ignition by the customary means, not shown, to effect the operation of the engine.

11 is an air pump suitably secured to the dash 1, or otherwise supported and connected at its discharge end by an air blast pipe 65 12 with the outer end of the mixing tube 8. 13 is the piston of the pump and 14 the handle at the rear end of the piston stem 15, the handle being preferably accessible from the driver's seat not shown, of the car.

With the construction shown, it will be apparent that preliminary to starting the engine, the operator will open valve 7 slightly, and then manipulate the pump to drive a blast of air through the mixing tube 75 to vaporize the gasolene dropping thereinto from the pipe 6. This produces a combustible mixture and such mixture is driven by the air pressure through the perforated nozzle into the manifold 4 and longitudinally 80 thereof so that practically the entire volume of the fine wet vapor shall be taken up or absorbed by the air to insure a proper explosive mixture, and this combustible mixture is drawn into the cylinders of the engine and ignited when the engine is cranked. Immediately after the engine is started the operator will cut off the supply of gasolene 85 from tank 5 if he has not previously done so, which tank is rendered inoperative until it 90 is again needed for priming purposes. The connection for supplying fuel to the carbureter is not shown, as it forms no part of the invention.

In Fig. 4, the tank 5 is shown as secured 95 to the dash and the handle of the valve 7 is disposed at the inner side of the dash to enable the operator to manipulate the valve conveniently from the driver's seat. In this case the pipe 6 is increased in length, but 100 communicates as explained with the mixing tube 8, and the air blast 12 from the pump, likewise communicates with said tube. The mixing tube will of course communicate with the manifold 4, the latter, the carbureter and 105 the engine being omitted from Fig. 4.

From the above description it will be apparent that I have produced a priming device embodying the features of advantage enumerated as desirable in the statement of 110 the object of the invention, and while I have illustrated and described the preferred em-

bodiments of the invention, it is to be understood that it is susceptible of modification in minor particulars without departing from the spirit and scope of the appended claim.

5 I claim:

The combination with an internal combustion engine having an intake manifold, a mixing tube having one end projecting into the manifold and provided with fine jet ori-

10 fices facing longitudinally of the manifold, an air pump connected to the opposite end

of said tube, a gasolene tank having a pipe terminating in a fine discharge orifice in communication with the said tube, and a valve for controlling said pipe.

In testimony whereof, I affix my signature, in the presence of two witnesses.

LE ROY WERTS.
